E. LUNDGREN

UNDERFEED STOKER

Filed April 19, 1923

UNITED STATES PATENT OFFICE.

EDWIN LUNDGREN, OF FREDERICK, MARYLAND, ASSIGNOR TO COMBUSTION ENGINEERING CORPORATION, OF NEW YORK, N. Y., A CORPORATION OF NEW YORK.

UNDERFEED STOKER.

Application filed April 19, 1923. Serial No. 633,096.

My invention relates to underfeed stokers and more particularly to underfeed stokers of the inclined multiple retort type.

The principal object of the invention is 5 to provide novel and improved means for controlling the admission of air to the air supplying surfaces of the underfeed section of stokers of the type above indicated.

The following is a description of my in- 10 vention, reference being had to the accompanying drawings, in which,

Figure 1 is a longitudinal sectional view, partly in elevation, of a portion of an underfeed stoker embodying features of the 15 invention in their preferred form;

Fig. 2 is a detail sectional view, on an enlarged scale, of a portion of the tuyère structure of the stoker illustrated in Fig. 1;

Fig. 3 is a detail plan view of one of the 20 tuyère blocks forming a component part of the tuyère structure; and

Figs. 4 and 5 are views similar to Fig. 2 but showing modified forms of tuyère structures.

25 The underfeed stoker illustrated in the drawings is provided with a wind box 2 and downwardly inclined fuel retorts 4 that are arranged side by side and spaced apart with a tuyère structure 6 spanning the margins of the side walls of adjacent retorts, the tuyère structure being made up of tuyère blocks.

The tuyère blocks as usual are arranged one above the other in overlapping relation 35 and the blocks are secured together by a depending hook-shaped member 8 on the under side of each of them that extends through an aperture in the next block below and hooks under the forward end wall of the aperture. Each block is provided with a depending marginal rib 10 that rests upon a rib 12 on the top side of the next block below. The underside of each rib 10 is corrugated so as to cooperate with the adjacent 40 rib 12 to form air openings 14. These air openings 14 are in communication with the wind box through the spaces between the blocks inside of the ribs 10 and 12.

In the present construction the desired 50 air control for the different parts of the fuel bed is accomplished by the construction and arrangement of the tuyère blocks themselves, or by means associated with each tuyère block. In the construction illustrated in 55 Figs. 1, 2 and 3 of the drawings, each tuyère

block is provided with an air obstructing rib 16 extending across the forward end of the block inside of the rib 12 so as to restrict the passage of air through the spaces between the blocks and hence through the air 60 openings 14. By making the ribs 16 of the several tuyère blocks of different heights it will be apparent that the supply of air to the different parts of the fuel bed may be regulated as desired. As shown, the ribs 16 65 are removably mounted on the tuyère blocks so as to enable the proper sizes of ribs to be conveniently supplied to the different tuyère blocks to secure the result desired. To provide for this, the ribs are each pro- 70 vided with a longitudinally extending depending tongue 18 which is received in a slot in the tuyère block.

In the construction shown in Fig. 4 the desired air control is secured by varying the 75 thickness of the walls of the tuyère blocks inside of the ribs 10 and 12.

In the construction shown in Fig. 5 the desired air control is secured by making the air openings 14 of the several tuyère blocks 80 of different sizes.

As will be evident to those skilled in the art, my invention permits of various modifications without departing from the spirit thereof or the scope of the appended claims. 85

What I claim is:

1. An underfeed stoker having, in combination, a wind box, a plurality of downwardly inclined fuel retorts arranged side by side and spaced apart, and fuel supporting tuyère blocks spanning the margins of the side walls of adjacent retorts with the air passages of different blocks of different capacities so as to cause air passing from the wind box through the blocks to be supplied in different quantities to the fuel supporting surfaces of the different blocks, respectively, said blocks having provision for varying the capacity of their air passages. 95

2. An underfeed stoker having, in combination, a wind box, a plurality of downwardly inclined fuel retorts arranged side by side and spaced apart, fuel supporting tuyère blocks arranged in overlapping relation spanning the margins of the side walls of adjacent retorts, and air obstructing members of different sizes removably mounted on the blocks, respectively, for obstructing the passage of air through the 100 105 110

blocks from the wind box so as to cause air passing from the wind box through the blocks to be supplied in different quantities to the fuel supporting surfaces of the different blocks, respectively.

3. An underfeed stoker having, in combination, a wind box, a plurality of downwardly inclined fuel retorts arranged side by side and spaced apart, fuel supporting 10 tuyère blocks arranged one upon the other in overlapping relation and spanning the margins of the side walls of adjacent retorts, the forward portion of each of said overlying blocks having a depending mar-

ginal rib that rests upon the top of the next 15 underlying block, the under side of each of said ribs having a plurality of corrugations so as to cooperate with the top side of the underlying block to form tuyère openings leading into the fire box of the furnace, 20 and air obstructing means associated with each block for obstructing the passage of air through the blocks from the wind box so as to cause air passing from the wind box through the blocks to be supplied in 25 different quantities to the fuel supporting surfaces of the different blocks, respectively.

EDWIN LUNDGREN.
